(57) **CLAIM**

The ornamental design for a feed housing for a hydrocyclone feed assembly, as shown and described.

DESCRIPTION

FIG. 1 is a top, right, front, perspective view of a feed housing for a hydrocyclone feed assembly showing our new design;

FIG. 2 is a top, left, rear, perspective view thereof;

FIG. 3 is a top left perspective view thereof;

FIG. 4 is a front elevational view thereof;

FIG. 5 is a rear elevational view thereof;

FIG. 6 is a right, side elevational view thereof;

FIG. 7 is a left side elevational view thereof;

FIG. 8 is a top view thereof; and,

FIG. 9 is a bottom view thereof.
